Primary Examiner—Robert C. Spangler

[57] **CLAIM**

The ornamental design for a packaging container for a bottle or the like, substantially as shown and described.

DESCRIPTION

FIG. 1 is an exploded top perspective view of a packaging container for a bottle or the like showing my new design;

FIG. 2 is an exploded side elevational view, the opposite side being the same in appearance;

FIG. 3 is an exploded elevational view looking from the right of FIG. 2, the opposite side being the same in appearance;

FIG. 4 is a bottom plan view; and

FIG. 5 is a top perspective view showing the container in the closed position.
